CLAIM

The ornamental design for a cupboard light, as shown and described.

DESCRIPTION

FIG. 1 is a front elevational view of a cupboard light showing the new design;

FIG. 2 is a rear elevational view thereof;

FIG. 3 is an enlarged left-side elevational view thereof;

FIG. 4 is an enlarged right-side elevational view thereof;

FIG. 5 is a top plan view thereof;

FIG. 6 is a bottom plan view thereof;

FIG. 7 is a top, front, right perspective view thereof;

FIG. 8 is a front, left perspective view thereof;

FIG. 9 is a top, left, rear perspective view thereof;

FIG. 10 is another top, left, rear perspective view thereof;

FIG. 11 is a bottom, left, rear perspective view thereof;

FIG. 12 is another top, left, rear perspective view thereof;

FIG. 13 is a top, right, rear perspective view thereof;

FIG. 14 is another top, left, rear perspective view thereof;

FIG. 15 is an enlarged partial view of FIG. 1;

FIG. 16 is an enlarged partial view of FIG. 7;

FIG. 17 is another enlarged partial view of FIG. 7;

FIG. 18 is an enlarged partial view of FIG. 8;

FIG. 19 is an enlarged partial view of FIG. 9;

FIG. 20 is an enlarged partial view of FIG. 10;

FIG. 21 is an enlarged partial view of FIG. 11;

FIG. 22 is an enlarged partial view of FIG. 12;

FIG. 23 is an enlarged partial view of FIG. 13; and,

FIG. 24 is an enlarged partial view of FIG. 14.
